UNITED STATES PATENT OFFICE.

GUSTAV A. CARLSON, OF CHICAGO, ILLINOIS, ASSIGNOR TO THE BOYE NEEDLE COMPANY, OF CHICAGO, ILLINOIS, A CORPORATION OF ILLINOIS.

HOLDER FOR PENCILS, FOUNTAIN PENS, ETC.

1,412,505.

Specification of Letters Patent. Patented Apr. 11, 1922.

Application filed November 19, 1920. Serial No. 425,193.

To all whom it may concern:

Be it known that I, GUSTAV A. CARLSON, a citizen of the United States, residing at Chicago, in the county of Cook and State of Illinois, have invented a new and useful Improvement in Holders for Pencils, Fountain Pens, Etc., of which the following is a specification.

This invention relates particularly to a holder for pencils, fountain pens, or the like; and the primary object is to provide an improved device of this character which can be manufactured very cheaply.

The invention is illustrated in its preferred embodiment in the accompanying drawing, in which—

Figure 1 represents an edge elevational view of the improved device; Figure 2, an elevational view of the device, looking at the side which is equipped with the resilient ring for holding a pencil; Figure 3, a plan view of the device; Figure 4, a broken sectional view taken as indicated at line 4 of Fig. 2; Figure 5, a bottom plan view of a ring-securing clip employed; Figure 6, an elevational view of the same; and Figure 7, a sectional view taken at the line 7 of Fig. 6.

In the form illustrated, the device comprises an inverted U-form clip A which is adapted to be applied to the pocket of a garment; a coil-supporting clip B secured to the inner arm of the member A; and a resilient ring or annular coil C carried by the clip B.

The member A may be of any approved form, and may be provided with any suitable means for attaching it to a pocket or garment. In the form shown, the member A has an inner arm 1, an outer arm 1^a, and a curved portion, or loop, 1^b, uniting said arms at their upper ends. The member A preferably is formed of sheet metal, and the edge portions of the arm 1 are provided with rearwardly and inwardly-turned flanges 2 which afford vertical guides for the clip B. As shown, the guides 2 extend from near the upper end of the arm 1 to an intermediate point. Between the arm is afforded a channel 3 which is adapted to accommodate the cloth of a pocket; and the arm 1 is shown provided with a forward projection 4 adapted to engage the material of the pocket. The lower end of the arm 1^a is curved as indicated, so as to have a portion underlying the stud or embossment 4, thus aiding the clamping of the cloth of the

pocket in such manner as to prevent loss of the clip.

The coil-carrying clip B comprises a piece of sheet metal having a vertical base portion 5 adapted to slip into and be secured in the guides 2, and a reduced extension 5^a which is bent back and extended downwardly substantially parallel with the part 5, as will be understood from Figs. 6 and 7. At its lower portion, the part 5 is provided with curved arms 6 which form segments of a circle. The arms 6 are formed by providing the part 5 at its lower end with reduced lateral extensions and shearing the metal as indicated at 6^a. The members thus afforded are bent or offset from the plane of the part 5, as indicated at 6^b; and the segmental arms 6 are carried by the offset portions 6^b.

The member 5^a is reduced in cross-section near its lower end; and at its lower end the member 5^a is provided with lateral projections 7^a which are separated from the base portions of the segmental arms 6 by spaces 8. It will be seen from Fig. 5 that the projections 7^a form rudimentary arms which are complementary to the segmental arms 6.

The clip B is applied to the clip A by slipping the plate or part 5 into the guides 2 and clenching the flanges.

The coil C preferably is formed from a straight coil having circular convolutions 9, the coil being bent into circular form. The convolutions at the ends of the coil are entered on the rudimentary arms 7^a, while the segmental arms 6 are entered between convolutions near the ends of the coil and passed into the annular ring which the coil affords, as will be best understood from Fig. 4. It will be understood that the convolutions are somewhat distorted by entering the arms therein in the manner described, and the natural resiliency of the member C will serve to hold the members securely in position.

The construction is such as to provide a secure attachment between the annular coil C and the supporting member A; and it will be understood that the connection is such that the coil C will be maintained in a plane at right angles to the arm 1. The segmental arms 6 serve to support the coil in this position, without interfering with the expansion of the coil when a pencil or pen is inserted; and the relation of the end portion of the member 5^a to the base portions 110

of the segmental arms 6 is such as to effectively prevent disengagement of the ends of the coil from the supporting member. The arms 6 are somewhat resilient, and are 5 capable of yielding in the event that a very large pencil, or large fountain pen is inserted in the loop. However, the main accommodation of the resilient loop C to the pencil or pen is effected by the expansion 10 of the resilient ring when the pencil is introduced.

In the form illustrated, it will be noted that the attaching clip B is substantially of inverted U-form, and is adapted to support 15 the resilient coil C some distance below the upper end of the member A and preferably at a point near the middle of the member A. Thus, when the device is applied to the pocket of a vest or coat in the usual manner, 20 the resilient coil C is located in the pocket some distance below the upper edge thereof, so as not to be visible. Ordinarily, in inserting a pencil, the segmental arms 6 serve sufficiently to maintain the coil C in the 25 horizontal position and insure the ready entrance of the pencil into the coil. In case a very large fountain pen is to be introduced, the user may additionally support the coil by the thumb and finger while the coil is 30 being forcibly expanded to admit the pen.

It will be understood that the clip A which is adapted to be attached to the pocket of a vest or coat, or to any article of wearing apparel, may be of any suitable 35 form, and may be provided with any suitable means for securely attaching it to the garment. It will be understood also that the member B which is provided with means for supporting the coil C in a plane at right angles to the member A, may be secured to the member A in any suitable manner. The construction shown is preferred, however.

It will be noted that the construction permits the use of a coil having substantially 45 circular convolutions. In practice, it is found that a coil having convolutions of comparatively small diameter may be used; hence, both on account of the cheapness of manufacturing a coil with circular convolutions and on account of the reduced amount 50 of wire required, the cost of manufacturing the improved pencil clip is reduced.

The foregoing detailed description has 55 been given for the purpose of understanding only and no unnecessary limitations should

be understood therefrom, but the appended claims should be construed as broadly as permissible in view of the prior art.

What I regard as new, and desire to secure by Letters Patent, is:

1. A holder for a pencil or the like comprising a supporting member adapted to be applied to an article of wearing apparel, a clip secured to said member and provided with segmental arms, and a resilient annular coil mounted on said clip, said segmental arms extending within said coil. 60

2. A device of the character set forth comprising a supporting clip adapted to be applied to an article of clothing, a coil-supporting clip secured to said first-named clip and provided with segmental arms and provided also with a member interposed between the base portions of said segmental arms and spaced with relation thereto, and a resilient 70 annular coil having end convolutions engaging said interposed member, said segmental arms being entered between convolutions near the ends of the coil and extending in opposite directions into the coil. 75

3. A device of the character set forth comprising a main supporting clip adapted to be attached to an article of clothing, a U-shaped coil-supporting clip having one member provided with a pair of segmental arms 85 offset from the plane of said member and having another member provided with rudimentary arms interposed between the base portions of said segmental arms, and an annular coil having end portions mounted on 90 said segmental arms and having end convolutions engaging said rudimentary arms. 95

4. A device of the character set forth comprising a main supporting clip adapted to be attached to an article of clothing, said 100 clip having an arm equipped with guide flanges, an inverted U-shaped coil-supporting clip having a member secured in said guide flanges and equipped at its lower end with a pair of segmental arms and having 105 also a member with its lower end interposed between the base portions of said segmental arms, and an annular coil having end portions mounted on said segmental arms and having end convolutions interposed between the base portions of said segmental arms and the lower end of said last-mentioned member.

GUSTAV A. CARLSON.
